UNITED STATES PATENT OFFICE.

RUDOLPH JENTZEN AND CARL HÖGE, OF ALTONA, GERMANY.

LOCK.

SPECIFICATION forming part of Letters Patent No. 654,003, dated July 17, 1900.

Application filed May 15, 1899. Serial No. 716,820. (No model.)

To all whom it may concern:

Be it known that we, RUDOLPH JENTZEN and CARL HÖGE, subjects of the Emperor of Germany, residing at Altona, Germany, have 5 invented certain new and useful Improvements in Locks, of which the following is a specification.

Our present invention relates to safety mechanism adapted to be applied to any kind 10 of locks and to be locked by grooved keys, so that they can be opened only by means of the keys which have been employed for locking them.

The improvements consist in the features 15 of construction and combination of parts fully described hereinafter, and specifically pointed out in appended claims.

In order that the invention may be the more 20 readily understood and carried into effect, reference is hereby made to the accompanying drawings, in which—

Figure 1 is a front elevation of a padlock provided with our improvements. Fig. 2 is a side elevation of same. Fig. 3 shows a section on line $\alpha\alpha$ of Fig. 4. Fig. 4 is an inner view of the mechanism in inoperative position, one of the plates of the padlock being moved aside. Fig. 5 shows the same mechanism actuated by means of a key to permit 30 the introduction of a shouldered pin.

In the drawings like numerals refer to like parts throughout all the figures.

Referring to the several views of the drawings, 1 represents the box or casing of a padlock, having two plates 2 3 riveted or otherwise secured onto the cylindrical box or casing and provided with ears or extensions 8 8, perforated or apertured to receive pins 4 4, preferably made one with an eye 5, carrying 35 a ring 7, receiving the end link of a chain 9, the other end of which carries a pin 10, provided with shoulders or circular steps, as hereinafter described. The bottom plate 3 is provided with a circular opening 11 and an opening 12 for the passage of the key.

To the center of the plate 2 and within the padlock is secured a shaft 13, over which are fitted the extensions 15 of sections 14 14' 14² 14³ 14⁴, freely sliding over each other and 40 moving about said shaft 13. The extension 15 of each section is provided with gear-teeth, and each section has four openings 21 21' 21²

21³, which when in inoperative position register with each other. The openings indicated by numeral 21 register with opening 11 55 in the plate 3 and with a recess 2', provided in plate 2. All the openings 21 have equal diameter except opening 21 of section 14⁴, adapted to slide over the inner surface of plate 2, said opening being of smaller diameter than the others.

Each toothed extension 15 of the sections 14 meshes with a corresponding segment 16, and said segments are equal in number with the sections 14 and are fitted against each other and over a stationary pin 17, about 60 which they may be moved. Between each pair of adjacent segments 16 is inserted a disk 19, and each segment 16 is provided with a groove 40, engaged by a spring 20, attached 65 to a rod 22 and fitted around a rod 22', said rods being fixed to the inner side of the plate 2.

45 is a stop-pin for the key, and 18 the pindle on which the key is fitted when applied to the lock.

The pin 10 has annular shoulders of different diameters, and upon inserting it in the lock through the opening 11 the first shoulder corresponds to the thickness of plate 3, each of the five following shoulders corresponding 70 to the five sections 14 to 14⁴ and the end shoulder or flange of said pin corresponding to the depth of the recess 2', on which the pin rests in locking position.

The operation of the device is as follows: 85 The locking of a door is effected by passing the chain 9 through eyes or staples secured to such door and its frame, and the grooved pin 10 is inserted into the opening 11 of the lock. When the latter is in inoperative position, as shown in Fig. 4, said pin cannot engage the bottom of the recess 2', as it is arrested by plate 14⁴, the opening 21 of which is too small to permit the passage of the end of the pin. Before inserting the pin 10 a 90 grooved key is fitted to the pindle 18, said key having branches corresponding to the thickness of the sections 14 to 14⁴ and of proper length to engage the sides or edges of segments 16, so that upon turning the key 95 the latter will be rotated a distance corresponding to the length of the respective branches and the segments will in turn rotate the plates 14 to the same extent or until the

large opening in the plate 14⁴ is brought into line with the corresponding openings in the other plates, and thus permit the insertion of the pin to the full depth. Upon withdrawing the key the springs 20 pressing on the segments bring them into their normal positions so far as permitted or until the edges of the openings in the sections engage the adjacent shoulders in the pin 10, thus preventing the withdrawal of the latter except through the medium of the locking-key, whereby the parts are returned to their registering positions.

Having thus described our invention, what we claim as new, and desire to obtain by Letters Patent, is—

1. In a safety mechanism for locks, the combination with a casing having plates 2 and 3, of a shaft centrally mounted in one of said plates, a plurality of segments mounted on said shaft and each provided with a toothed extension and having a series of openings therein, one of said openings in one of the

segments being of less diameter than the other openings, the pin 10 adapted to engage 25 said openings and means engaging the toothed extensions of said segments whereby the latter may be operated.

2. In a mechanism of the character described, the combination with the casing, a central shaft in said casing, a series of segments mounted on said shaft and having toothed extensions, a pin 17 in the casing, a series of toothed segments loosely mounted on said pin, and adapted to engage the extensions aforesaid, disks between said last-named segments, springs for operating the latter secured to the casing, a key-slot in one of the plates, a key-pintle, and suitable stop for the key, fixed in the case, substantially 40 as set forth.

RUDOLPH JENTZEN.
CARL HÖGE.
